UNITED STATES PATENT OFFICE

JOHN C. SCHEELER, OF BUFFALO, NEW YORK, ASSIGNOR TO BUFFALO WIRE WORKS CO. INC., OF BUFFALO, NEW YORK, A CORPORATION OF NEW YORK

COUPLING FOR FENCE POSTS AND THE LIKE

Application filed January 18, 1929. Serial No. 333,262.

This invention relates to a coupling for detachably connecting posts arranged at the opposing ends of portable wire fence sections and other enclosures, such as wire 5 guards having round iron frames, but it is to be understood that this coupling may be used for other analogous purposes.

The object of this invention is the provision of a coupling of this character which is comparatively simple and inexpensive in construction and in which the main elements are permanently connected as a unit whereby the mounting of this coupling on the parts to be connected can be effected more conveniently and the several parts of the same are also not likely to be scattered while the same is being stored or shipped.

In the accompanying drawings:—

Figure 1 is a fragmentary elevation of two adjacent sections of a portable wire fence or guard which have been erected on the ground and connected at their opposed vertical ends by couplings which are constructed in accordance with this improvement.

Figure 2 is an elevation, on an enlarged scale, of this coupling applied to the end post of two fence sections or like structure.

Figure 3 is a horizontal section taken on line 3—3 Fig. 2.

Figure 4 is a perspective view of the coupling in which the several parts thereof have been assembled in the normal position which they occupy while in use.

Figure 5 is a similar view showing the several parts of the coupling separately preparatory to being assembled after being manufactured.

Similar characters of reference in the following description indicate like parts in the several views of the drawings.

Referring to Fig. 1 which shows two sections of a portable wire fence connected by two couplings made in accordance with the present improvement, each of these sections 45 consists of a frame having upper and lower horizontal bars 10, 11, upright posts 12 connecting the corresponding ends of said horizontal rods, and one or more intermediate posts 13 which connect the intermediate 50 ate parts of these horizontal rods. At its

lower end each of the posts is provided with a downward extension 14 forming a spike or spur which is adapted to be driven into the ground for holding the respective fence section in an upright position.

55

As is well known, these fence sections may be either placed end to end in line with each other, or at an angle relatively to one another, as best suits the particular character of fence, closure or pen which is desired to be erected.

60

When thus mounted on the ground, the upright posts or rods 12 of two adjacent fence sections are connected by one or more couplings which contain the present invention. Each of these couplings is preferably constructed as follows:—

65

The body of the coupling comprises two plates which in their normal operative position oppose each other and each of which is preferably stamped or bent into corrugated form out of a single sheet of metal. One of the metal plates is bent to form two semi-cylindrical jaws 15, 16 which are arranged side by side and between opposite ends of this plate, the concave sides of these jaws facing inwardly while the convex sides thereof face outwardly. At one end of the plate having the jaws 15, 16 the same is provided with a single pivot eye 17 which is formed by curling or bending the metal of this plate 70 into cylindrical form, this pivot eye being preferably arranged midway between the top and bottom edges of this plate. At the opposite end of this plate the same is provided with two locking eyes 18, 18 which are arranged adjacent to the upper and lower edges of this plate and are separated by an intervening space, and are formed by curling the metal of this plate.

75

The other plate is bent to form two semi-cylindrical jaws 19, 20 which are arranged side by side and intermediate of the ends of this plate, the concave sides of these jaws facing inwardly and the convex sides thereof facing outwardly. At one end of the last-mentioned plate the same is provided with two pivot eyes 21, 21 which are arranged adjacent to the upper and lower edges of this plate and are separated by an intervening space, these last-mentioned eyes being formed 85

95

100

on the respective plate by curling the metal of the same into cylindrical form in the same manner in which this is done when forming the eye 17 on the companion coupling plate.

5 At the opposite end of the plate which has the two pivot eyes 21, 21, a single locking eye 22 is formed midway between the upper and lower edges of this plate, this locking eye 22 being formed by bending or curling 10 the metal of this plate.

These two coupling plates are preferably permanently connected by placing the single pivot eye 17 of one of the plates between the double pivot eyes 21 of the other plate so 15 that these eyes are axially in line with each other, and then inserting a pivot pin or pindle 23 through these eyes and upsetting the upper and lower ends thereof so that this pivot pin cannot be displaced, thereby permanently connecting the two coupling plates 20 but permitting them to swing relatively to each other for spreading these plates apart or bringing them together.

When spread apart, these two plates can 25 be passed along opposite sides of two posts 12, 12 and thereafter these two plates are swung toward each other so that the two jaws in each plate engage with the corresponding sides of two posts and the single 30 locking eye 22 of one plate enters the space between the two locking eyes 18 of the other plate, and the eyes of these two plates cross each other.

While the plates are in this position the 35 same are interlocked at those ends thereof which are opposite the pivotally connected ends by inserting a locking pin 24 between the crossed eyes of the respective plates so that the jaws are securely held in operative 40 engagement with opposite sides of the fence posts, as best shown in Fig. 3. This locking pin may be provided at its upper end with a laterally projecting arm 25 which forms a stop adapted to engage with the upper edge 45 of one of the double locking eyes and thereby limits the downward movement of this pin after the parts have been assembled.

In this form of coupling the two plates 50 may be pressed against opposite sides of the respective pair of posts with comparatively heavy pressure, inasmuch as the plates are connected with each other at their extremities whereby the plates are prevented from spreading when subjected to pressure upon 55 being applied to the posts, thereby producing a better and stronger connection between the adjacent fence sections.

Moreover, the two sections or body plates 60 of the coupling, due to the permanent connection at one of the ends of these plates, render the same practically a unitary construction whereby the main parts of the same are not liable to be scattered and therefore does not require matching up two plates as 65 would be necessary if these plates were de-

tached. Obviously this facilitates the erection of a fence which is a considerable item in the matter of time when a fence of great length is being erected.

I claim as my invention:—

1. A coupling for connecting two fence posts or like members, comprising two plates which normally oppose each other and each of which is provided intermediate of its ends with two jaws adapted to engage with the 70 corresponding sides of said members, means for pivotally connecting one of the corresponding pairs of ends of the plates, and means for detachably connecting the other corresponding pair of ends of said plates. 75

2. A coupling for connecting two fence posts or like members, comprising two plates which normally oppose each other and each of which is provided intermediate of its ends with two jaws adapted to engage with the 80 corresponding sides of said members, pivot eyes arranged on one pair of the corresponding ends of said plates, a pivot pin passing through said eyes, locking eyes arranged on the other corresponding pair of ends of said 85 plates and crossing each other, and a locking pin insertable between said crossed locking eyes.

3. A coupling for connecting two fence posts or like members, comprising two plates which normally oppose each other and each of which is provided intermediate of its ends with two jaws adapted to engage with the 90 corresponding sides of said members, one of said plates being provided at one end with a single pivot eye and the other plate being provided at the corresponding end with two pivot eyes which receive between them said single pivot eye, a pivot pin passing through said pivot eyes, one of said plates being provided at its opposite end with a single locking eye and the other plate having the corresponding end provided with two locking eyes which receive said single locking eye between them, said locking eyes crossing each other 95 in the assembled position of said plates, and a locking pin insertable between said crossed locking eyes.

In testimony whereof, I hereby affix my signature.

JOHN C. SCHEELER.
